HAT IRONING MACHINE

Paul Schultze, Danbury, Conn., assignor to Doran Brothers, Danbury, Conn.

Application May 29, 1935, Serial No. 24,065

14 Claims. (Cl. 223—21)

This invention relates to hat ironing machines or the like.

One of the objects of this invention is to provide a machine for ironing or for performing various other operations upon a hat. Another object is to provide a machine of the above nature which is thoroughly practical and highly efficient in the performance of its operation. Another object is to provide a machine of the above nature which will consistently and uniformly process the crown portion of a hat. Another object is to provide a machine of the above nature which is sturdy and capable of long continuous use. Another object is to provide a machine of the above nature capable of efficiently ironing the band portion of a hat. Another object is to provide a machine of the above nature which is simple and inexpensive to construct and which may be readily operated by an unskilled operator. Other objects will be in part obvious or in part pointed out hereinafter.

The invention accordingly consists in the features of construction, combinations of elements and arrangements of parts, as exemplified in the structure to be hereinafter described, and the scope of the application of which will be indicated in the following claims.

In the accompanying drawings, in which is shown one or more of the various embodiments present in this invention,

Figure 1 is a perspective view of the machine, certain of the parts thereof being broken away;

Figure 2 is a fragmentary side elevation of certain portions of the machine;

Figure 3 is an end elevational view of the parts shown in Figure 2;

Figure 4 is a vertical section of the iron which I prefer to use in my machine; and

Figure 5 is a rear elevation of the iron shown in Figure 4.

Similar reference characters refer to similar parts throughout the several views of the drawings.

As conducive to a better understanding of certain features of this invention, it might here be pointed out that considerable difficulty is often encountered in properly ironing or luring the band portion of the crown of a hat or that portion of the crown immediately adjacent the brim. The central part of the iron usually cannot contact the band portion in a thorough and desirable manner and accordingly the band portion is poorly ironed. It is, of course, important that this part of the hat be treated as thoroughly as the other portions in order that it may

have the requisite stiffness to support the crown of the hat. Still further difficulties are encountered in effectively treating the "square" of a hat, the "square" being that portion of the crown lying between the sides and top thereof. This latter difficulty is usually encountered because of the inability of the iron to correctly follow the square. One of the various objects of this invention is to provide a machine in which the above-mentioned difficulties as well as many others are successfully overcome.

Referring now to Figure 1 in detail, there is generally indicated at 10 a standard, which may be of any suitable construction, having mounted thereon or integral therewith a frame or housing 10a which is adapted to carry certain moving parts of my machine in a manner to be more fully described hereinafter. A bore extends throughout frame 10a substantially parallel to the top of standard 10 and has rotatably mounted therein on suitable bearings a shaft 11 which may be driven in any suitable manner as, for example, by gears 11a.

Shaft 11 extends from the left-hand side of housing 10a, as viewed in Figure 2, and upon this end of the shaft a hat block 12 may be detachably mounted upon a chuck 13. Chuck 13 may be of any suitable construction but preferably includes a suitable number of jaws 13a, connected to a sliding collar 13b and operated thereby to grasp hat block 12. Collar 13b is connected to a handle or lever 14 by suitable links 14a, lever 14 being pivotally mounted on a suitable boss extending from housing 10a. Thus, when lever 14 is swung to the left, as viewed in Figure 1, collar 13b slides to the right to cause jaws 13a to release their grip on hat block 12 and conversely, swinging of lever 14 to the right causes the jaws to grip the hat block. A preferred embodiment of this structure is set forth in more detail in Patent No. 1,944,655 issued to J. F. Doran.

A worm gear 15 is secured to and is rotatable with shaft 11 and drives a gear 16 suitably supported in standard 10. A connecting rod 17 is pivotally secured to gear 16 and to a bracket 18, bracket 18 being connected to a rack 19. Thus, upon the rotation of gear 16, rack 19 reciprocates in guides 20 and 21. Guide 20 may extend integrally from the lower portion of standard 10 while guide 21 may be integral with a protruding portion 10b of the standard.

Portion 10b has a vertical bore formed therein in which is mounted a shaft generally indicated at 22. Shaft 22 preferably extends below portion 55

10b and has mounted on the end thereof a bracket piece 23, which, as may be clearly seen in Figure 2, is detachably secured to shaft 22 by way of a bolt 23a extending therethrough.

5 Bracket piece 23 includes a spring housing 23b (Figure 3) which receives through suitable bores a stud 24 (Figures 2 and 3). Spring housing 23b has a cover plate 23c secured thereto by means of suitable screws 23d. A suitable number of coil 10 springs 25 are disposed about stud 24 within housing 23b. One end of each of springs 25 is secured to stud 24 while the other ends thereof are secured to housing 23b, thus urging stud 24 in a counterclockwise direction as viewed in Figure 2.

15 Referring to Figures 2 and 3, a bifurcated arm generally indicated at 26 has a pair of prongs 27 and 28 (Figure 3) which extend about spring housing 23b and are secured to stud 24. More specifically, suitable clamping brackets 29 and 20 30 are secured to prongs 27 and 28 by bolts 31 (Figures 2 and 3) which, when taken up, force the prongs and the clamping members to rigidly secure these parts to stud 24.

An adjusting nut member generally indicated 25 at 32 (Figures 1 and 3) is secured on end 24a of stud 24. Nut member 32 has a segmental portion 32b formed thereon provided with a plurality of teeth 32c (Figure 1). Portion 32b of nut member 32 is preferably provided with suitable indicia 30 indicating the tension of springs 25 and the nut may be held in any position of adjustment by a manually operable stud 33 extending through a suitable boss 90 formed on arm 26. The end of stud 33 is threaded and the threads mesh with 35 teeth 32c on nut 32. Thus when stud 33 is turned, nut 32 is swung to vary the tension of springs 25 and the desired tension is indicated by a pointer 91 which lies over the indicia on nut 32 (Figure 5).

40 Referring again to Figure 1, it will now be seen that, upon rotation of gears 11a, hat block 12 is rotated. Likewise, gear 16 rotates to actuate connecting rod 17 and accordingly causes rack 19 to reciprocate. As better shown in Figure 2, shaft 22 has secured on its upper end, a gear 22a which meshes with rack teeth 19a of rack 19 (see Figure 1). Thus as rack 19 reciprocates, it imparts corresponding reciprocal rotation to shaft 22. As arm 26 is connected to shaft 22 by way 45 of bracket piece 23, it reciprocates with the shaft in a vertical direction with respect to frame 10. It might here be pointed out that, under certain circumstances, suitable speed change mechanism may be employed instead of gears 11a in Figure 1 50 as, for example, the mechanism shown in the Letters Patent No. 1,944,655, issued to J. F. Doran.

55 By pivoting arm 26 at a point spaced substantially below rack 19, the force necessary to swing arm 26 away from hat block 12 is considerably less than the force which would be necessary were arm 26 pivotally mounted in the vicinity of rack 19, and this because the angular movement of the swinging arm, when the iron is operating on the side of a hat crown and passing from the 60 major to the minor axis of the oval, is considerably less than it would be were arm 26 pivoted adjacent rack 19. Also, hat bodies of greater depth can be accommodated when arm 26 is mounted in this position substantially as described. Furthermore, since the difference between the long and short radii of the hat body oval is generally about three quarters of an inch, the angular movement of the arm at the radius where springs 65 25 are connected is so small that it is practically negligible. It follows that the tension of the

springs remains substantially constant with the resulting advantage of substantially uniform ironing pressure.

As is more clearly shown in Figures 1 and 2, an iron generally indicated at 34 is secured to a 5 bracket 35. Bracket 35 has a bore in which is secured a shaft 36 (Figure 2 and 3) the bottom of which is rotatably received in a web or journal 26a (Figure 3) extending between and preferably integral with sides 26b and 26c of arm 26. The 10 upper ends of arms 26b and 26c converge in a portion 26d (Figure 2) the top of which has a flat bearing surface which supports the flat bottom 35a of bracket 35. Thus, it will be seen that shaft 36 and accordingly iron 34 is free to pivot with 15 respect to arm 26. It is desirable that iron 34 be thus free to pivot in order that the square of a hat may be more effectively processed. As arm 26 swings around a hat mounted on hat block 12 (Figure 1), iron 34 being in contact with the 20 surface of the hat, the iron may find its own center as it passes over the square of the hat, thus completely ironing all portions of this part of the hat.

I have found that when the iron in many machines now in use reaches the extremity of its travel, that is, when it is operating on the band portion of a hat immediately adjacent to the brim thereof, the full pressure of the iron is not being exerted upon the band portion and accordingly this part of the hat is not sufficiently processed. To rectify this condition, I have provided a collar 37 (Figure 3) which is secured to and rotatable with shaft 36. One end of a spring 38 is secured to collar 37 and the other end thereof is secured to a screw 39 (Figure 2) which extends through a lug 40, preferably an upwardly projecting integral part of a collar 41. Collar 41 is secured to and rotatable with a shaft 42 which is pivotally received in a web or journal 26e 40 (Figures 2 and 3) extending between sides 26b and 26c of arm 26. A cramping lever 43 (Figure 2) is secured as by a pin 43a to the other end of shaft 42 and is so disposed that it abuts either one of two rollers 44 or 45 (Figure 1) rotatably mounted on a housing 10c extending below and secured to portion 10b of standard 10 as arm 26 approaches one limit or the other of its travel around hat block 12 as determined by the stroke of rack 19. Upon the abutment of lever 43 against either of the rolls, for example, if lever 43 engages roll 44, the lever is swung in a counterclockwise direction, as viewed in Figure 3, and accordingly a counterclockwise swing of lug 40 results. This causes a tensioning of spring 38 and a displacement of the lower end thereof to the left as viewed in Figure 3. Shaft 36 is secured to the upper end of spring 38 and is free to pivot. Accordingly, the displacement of spring 38 causes shaft 36 and iron 34 to pivot to the right. Thus the left 60 side of iron 34, as viewed in Figure 3, exerts additional pressure against the band portion of the hat to completely process that portion. It will be seen from the above that contact between cramping lever 43 and roll 45 produces a similar 65 increase of pressure by the right-hand side of iron 34, as viewed in Figure 3, when arm 26 swings around to its other extreme position.

As is more clearly shown in Figure 2, roller 44 is preferably mounted upon a bracket 46 which 70 is adjustably secured by means of a bolt 47 to housing 10c below portion 10b of standard 10. As roller 45 is similarly mounted (Figure 1) the position of either of the two rollers may be adjusted with respect to cramping lever 43 in order 75

to vary the additional pressure exerted by the vertical-edge portions of iron 34 against the band portion of the hat.

In order to facilitate the manual operation or application of iron 34, I provide a handle 48 (Figures 1 and 2) suitably secured to arm 26 and provided with a bore or channel 48a (Figure 3). Extending through channel 48a is a rod 49 which has secured to the top thereof a push button 49a. The lower end of rod 49 is loosely mounted in a latch 50 (Figure 2) which is secured to a shaft 51 journaled in arms 26b and 26c. As is best shown in Figures 1 and 2, latch 50 has an undercut portion providing a shoulder 50a (Figure 2) which abuts a projection 52 preferably integral with and extending from a hub or cap 53 mounted on top of and rotatable with shaft 22. Projection 52 is also provided with a bore in which is disposed a cushion 54 which, upon disengagement of latch 50 from projection 52 as by pressure on button 49a abuts journal 26a when there is no hat block on chuck 13. Hence pressure on button 49a releases latch 50 to permit manual operation of arm 26. If latch 50 is inadvertently disengaged by accidental pressure on button 49a, cushion 54 safeguards the iron and chuck by absorbing the shock which would otherwise result between them.

With reference to Figures 4 and 5, iron 34 preferably comprises a main body portion 55 (Figure 4) in which is formed a cavity 56 of suitable depth depending on the size of the iron and certain other circumstances. A block 57 is suitably secured in cavity 56 and has formed therein a compartment 58 in which a piece of bimetal 59 is secured by means of a screw 60 which extends into block 57. The rear surface 57a of block 57 is preferably in alignment with the bottom 55a of a chamber 55b formed in the rear of body portion 55. A cover plate 61 is suitably secured to the rear of body portion 55, and thus surface 55a forms with plate 61 chamber 55b in which is suitably disposed heat-producing resistance elements 62. A piece of mica 63 or the like is suitably secured to the back of cover plate 61 for electrical insulating purposes.

Cover plate 61 is provided with a recess 61a and an aperture 61b communicates therewith. Still referring to Figure 4, a terminal 64 extends through aperture 61b and is secured to plate 61, one end of resistance element 62 being connected to terminal 64. The other end of resistance 62 is connected to a terminal 67 (Figure 5) which in turn is connected to a lead 67a from electric cord 69. A terminal screw 65 (Figure 4) holds in place on terminal 64 a contact plate 66 which has an outwardly extending part 66a from which extends a portion 66b having mounted thereon a contact 66c. Portion 66b is preferably spaced a suitable distance from mica 63.

A second contact plate generally indicated at 68 in Figure 5 includes a portion 68a one end of which is secured to a post 80. As may be more clearly seen in Figure 4, post 80 is secured to cover plate 61 and extends therefrom through mica 63. Contact plate 68 (Figure 5) also includes a portion 68b which preferably extends from portion 68a preferably at right angles a distance sufficient to permit its end to register with portion 66a of contact plate 66. Portion 68b (Figure 4) has mounted on the underside thereof a contact 68c, and this contact registers with and is adapted to abut against contact 66c as will be more fully described hereinafter.

Referring to Figures 4 and 5, portion 68b on

contact plate 68 has threaded thereinto a terminal screw 85, and this terminal screw can be taken up to grip a lead 70 from electric cord 69. Thus, when contact is made between contact point 66c and contact point 68c resistance 62 is energized to heat the iron.

In order that the temperature of iron 34 may be automatically controlled, I have provided a pin 71 (Figure 4) slidably mounted in block 57, cover plate 61 and mica 63. One end of pin 71 abuts bimetal 59 and its other end abuts portion 68b of contact plate 68. Thus, as the temperature of iron 34 rises, bimetal 59 bends to force pin 71 against portion 68b and upon a predetermined maximum temperature being reached, the pressure of pin 71 overcomes the resiliency of portion 68b to separate the contact points and break the circuit. Therefore, the resiliency of portion 68b controls the breaking of the contact.

To predetermine the maximum temperature which causes the breaking of the contact, I provide a regulating device generally indicated at 72 (Figures 4 and 5) which varies the resiliency of plate 68. Regulating device 72 comprises a bracket 73 (Figure 5) secured to cover plate 61, and this bracket threadably receives a resiliency adjusting screw 74 which, as is better shown in Figure 4, bears against plate 68. Accordingly, as screw 74 is screwed against plate 68, the rigidity of the plate is increased and the pressure necessary to break the contact must, therefore, be greater. Similarly, as the pressure of screw 74 is released, the pressure of pin 71 necessary to break the circuit is decreased.

By referring to Figure 4, it will be seen that bimetal 59 is preferably located deep in the body of iron 34, that is, it is near the ironing surface where the heat is transferred to the hat. It is at this portion of the iron that temperature control is particularly important. Thus, by so positioning the temperature responsive bimetal 59, the iron temperature can be controlled within narrow limits.

Preferably I provide, in conjunction with the above-described temperature control, a suitable thermometer 75 (Figures 4 and 5) the recording part of which lies along the top of iron 34 and the sensitive part 75a of which is disposed within a bore 76 in iron 34. Thus, the maximum temperature desired may be readily predetermined and the danger of overheating the iron precluded.

Accordingly, it will be seen that I have provided a thoroughly efficient and practical construction in which the several objects mentioned hereinabove as well as many others have been successfully and efficiently accomplished.

As many possible embodiments may be made of the above invention and as many changes might be made in the embodiment above set forth, it is to be understood that all matter hereinbefore set forth, or shown in the accompanying drawings, is to be interpreted as illustrative and not in a limiting sense.

I claim:

1. In a machine of the character described, in combination, a hat support, means for rotating said support, an ironing tool adapted to operate upon the surface of a hat mounted on said support, means adapted to give said tool a traversing movement of substantially 180° across the surface of said rotating hat in a path extending over the crown thereof, means for urging said tool against said hat during said traversing movement, and means including a positively actuated lever adapted to cause the portion of the iron

nearest the band portion on each side of the hat to bear with increased pressure against the hat surface.

2. In a machine of the character described, in combination, a housing including a base portion, a shaft rotatably mounted in said housing, a support secured to said shaft adapted to have a hat mounted thereon, a rack slidably mounted in said base portion, a shaft rotatably mounted in 10 said base portion and extending therebelow, gear means secured to said second-mentioned shaft and adapted to mesh with said rack whereby said second-mentioned shaft is rotated upon reciprocation of said rack, a pair of rollers mounted on 15 opposite sides of said second-mentioned shaft, an arm pivotally associated with said second-mentioned shaft, an ironing tool pivotally mounted on said arm and adapted upon actuation of said arm by said rack to traverse the crown 20 surface of a hat mounted on said support, and means adapted upon engagement with one of said rollers to pivot said ironing tool as said tool approaches the band portion of the hat to cause the portion of said tool nearest the band portion of 25 the hat to bear with increased pressure against the hat surface.

3. In a machine of the character described, in combination, a housing, a shaft rotatably mounted in said housing, a hat support secured to said shaft, a shaft related to said housing and extending therebelow, means for rotating both of said shafts, a swinging arm pivotally associated with said second-mentioned shaft, said arm being adapted to move around and toward and 30 away from said hat support, an iron pivotally mounted on said arm, spring means coaxially disposed with respect to said arm and adapted to urge said arm against a hat mounted on said hat support whereby upon operation of said first- 35 mentioned means said iron traverses said rotating hat along a path extending from one band portion to the other band portion thereof, and means adapted as said iron approaches the band portions on each side of said hat to cause the portion 40 of the iron nearest the band portion to bear with increased pressure against the hat surface.

4. In a machine of the character described, in combination, a rotatable hat support, means for rotating said support, an ironing tool, means for urging said tool toward said hat support, means for moving said tool through an angle of substantially 180° over the surface of a hat mounted 50 on said support, and means for gradually varying the pressure exerted by portions of said ironing tool as said portions approach the band portions 55 on each side of said hat, said pressure being at a maximum when the iron is at the band portion limit of its travel.

5. In a machine of the character described, in combination, a rotatable hat support, a housing for said support, said housing including a base portion, a shaft rotatably mounted in said base portion, an arm secured to said shaft and pivotable toward and away therefrom, spring means 60 associated with said shaft and said arm and adapted to urge said arm toward said shaft, means for varying the tension in said spring means, an iron pivotally mounted on said arm, a cramping lever journaled in said arm, said lever being adapted to pivot said iron upon movement 65 of said lever, and means engaging said lever for effecting movement of said lever only when said iron is approaching the limit of its travel.

6. In a machine of the character described, in combination, a rotatable hat support, means for 75

rotating said support, a housing for said support and said means, said housing including a base portion, a shaft rotatably journaled in said base portion, means for rotating said shaft, an arm pivotally secured to said shaft and rotatable therewith, an iron pivotally mounted on said shaft, said iron being adapted upon rotation of said shaft to traverse the surface of a hat mounted on said support, a cramping lever journaled in said arm, spring means connecting said lever and said iron, and means mounted on said base portion and adapted upon abutment of said lever to tension said spring means and swing said iron whereby as said iron approaches the band of the hat, the portion thereof nearest the band bears 10 with increased pressure against the hat surface. 15

7. In a machine of the character described, in combination, a hat support, means for rotating said support, an arm movable circumferentially and radially of said hat support, an iron pivotally mounted on said arm, lever means journaled in said arm, spring means connecting said lever and said iron, and means for swinging said lever as said iron approaches the band portion of a hat mounted on said support to cause the portion of 20 the iron nearest the band portion of the hat to bear with increased pressure against the hat surface. 25

8. In a machine of the character described, in combination, a standard, a hat support rotatably mounted in said standard, an arm, means pivotally connecting said arm to said standard at a point spaced below the bottom of said standard, an iron pivotally mounted on said arm, means urging said arm toward said hat support, 30 said means including a plurality of coil springs whose axes are aligned with the pivotal axis of said arm, and means associated with said arm and said springs for varying at will the effective tension of said springs, said last mentioned 35 means including a gear segment enmeshed with a manually rotatable worm, said gear segment being operatively connected to said springs, and said worm being rotatably mounted on said arm. 40

9. In a machine of the character described, in combination, a standard, a hat support rotatably mounted in said standard, an arm pivotally connected to said standard and movable about said hat support, a pair of abutments secured to said standard, a lever pivotally mounted on said arm, 45 and adapted to engage one of said abutments during the movement of said arm about said hat support in each direction. 50

10. In a machine of the character described, in combination, a standard, a hat support rotatably mounted in said standard, a bifurcated arm pivotally connected to said standard and movable about said hat support through an angle of substantially 180°, a pair of abutments secured to said standard, a lever pivotally mounted on said 60 arm between the bifurcations thereof, and adapted to engage one of said abutments during the movement of said arm about said hat support in each direction, a post pivotally mounted in said arm, the lower end of said post lying between the bifurcations of said arm, means operatively connecting said lever and said post whereby upon abutment of said lever against one of said abutments said post is pivoted in one direction or another, and an iron secured to 65 said post. 70

11. In a machine of the character described, in combination, a hat support, means for rotating said support, an arm movable circumferentially and radially of said hat support, an iron piv- 75

totally mounted on said arm, lever means journaled in said arm, means connecting said lever and said iron, and means for swinging said lever as said iron approaches the band portion of a hat mounted on said support, to cause the portion of the iron nearest to the band portion of the hat to bear with increased pressure against the hat's surface, said last mentioned means including a movable abutment, the position of which may be varied at will to change the value of said increased pressure.

12. In a machine of the character described, in combination, a hat support, a hat iron support, an iron mounted on said iron support, means for effecting relative movement between said supports, the path of said movement extending substantially throughout an angle on the order of 180°, abutment means associated with said supports, said abutment means including members one of which is operably associated with said iron and engageable with another of said members at different points in said path of movement to vary the pressure of certain portions of said iron against certain portions of a hat mounted on said hat support at different points of said movement.

13. In a machine of the character described, in combination, a hat support, an iron support,

means for effecting relative movement between said supports, the extent of the path of said movement being on the order of 180°, means for effecting relative movement between said supports toward and away from one another, an iron mounted on said iron support and adapted to operate upon the surface of a hat mounted on said hat support, a pair of abutments secured to one of said supports, and means associated with the other of said supports and engageable with said abutments substantially at opposite ends of said path of movement to effect an increase of pressure between certain portions of said iron and certain portions of said hat.

14. In a machine of the character described, in combination, a hat support, an iron support, an iron mounted on said iron support for operating on a hat mounted on said hat support, means for effecting relative movement between said supports, means forming an abutment on one of said supports, and means associated with the other of said supports and engageable with said abutment to effect an increase of pressure between certain portions of said iron and certain portions of said hat.

PAUL SCHULTZE.
